MEANS FOR FORMING SHOES

Otto Anthony Dehne, Union, Mo.

Application January 12, 1938, Serial No. 184,514

11 Claims. (Cl. 12—1)

This invention relates in general to a method and means for making shoes and, more particularly, to certain new and useful improvements for the method and means for attaching uppers and 5 soles of so-called "stitch-down" type shoes.

It has long been the practice in the manufacture of shoes, and particularly shoes designed for children, to fabricate the shoe in the form of a so-called "stitch-down" type, that is to say, a 10 shoe in which the lower marginal edges of the upper are flanged outwardly and stitched to the upper face of the sole exteriorly of the upper. Frequently a welting strip is applied to the upper face of the flange prior to the stitching operation 15 for the dual purpose of improving the appearance of the shoe and increasing its wearing qualities.

The process of manufacturing stitch-down and other related types of shoes has been subject to several inherent difficulties. After the upper has 20 been lasted and the out-turned or stitch-down flange of the upper has been formed, the upper must be very carefully positioned over the sole prior to stitching and must be securely held during 25 the stitching operation, otherwise the outer peripheral margin of the sole in the finished shoe will be ragged and require trimming and the lasted upper of the shoe will be somewhat pulled out of normal shape. In order to overcome these 30 difficulties, it has been common practice to leave the lasted upper on the wooden last during the stitching operation. Although this procedure has to some extent eliminated the difficulties referred to, it has not been wholly successful and has 35 even introduced a further difficulty, since it has heretofore been found almost impossible to avoid deforming the inwardly presented bent-over margin of the flange along which the flange is integrally joined to the upper. Thus, the upper 40 will not come down sharply against the sole but will tend to curve arcuately outwardly adjacent the sole toward the stitch line by which the flange is joined to the sole.

My invention hence has for its primary objects 45 the provision of an improved method and means of manufacturing shoes and particularly shoes of the stitch-down type, in which the upper and sole may be readily secured together in a simple, convenient, efficient, and economical manner; in 50 which the stitch-down flange of the upper may be secured against the sole in a close-fitting, sharply defined, and undeformed manner; in which shoes of the type stated may be quickly manufactured 55 with a minimum of labor cost; and which is

otherwise highly efficient in the performance of its desired functions.

And with the above and other objects in view, my invention resides in the novel features of form, construction, arrangement, method, and 5 combination of the several parts presently described and pointed out in the claims.

In the accompanying drawings (4 sheets),

Figure 1 is a perspective view of a shoe-manufacturing machine constructed in accordance 10 with and embodying my present invention;

Figure 2 is a top plan view of the shoe-manufacturing machine;

Figure 3 is a fragmentary vertical sectional view of the machine; 15

Figure 4 is a horizontal sectional view of the machine, taken approximately along the line 4—4, Figure 3;

Figure 5 is a transverse fragmentary sectional view of the machine, taken along the line 5—5, 20 Figure 3;

Figures 6 and 7 are diagrammatic views, respectively, of the heel and toe shaping plates forming part of my present invention; and

Figures 8, 9, and 10 are diagrammatic sectional views, respectively, illustrating the progressive stages in the manufacturing of a shoe in accordance with my present invention. 25

Referring now in more detail and by reference characters to the drawings, which illustrate a preferred embodiment of my present invention, A designates a preferably rectilinear machine base or frame having four supporting legs 1, 2, 3, 4, mutually connected primarily for added rigidity and strength by means of preferably integrally formed cross-braces 5, 6, 7, 8, the latter or front cross-brace 8 preferably being widened and provided with a pair of vertically extending guide slots 9, each having at its lower extremity a laterally extending detent slot 10, all for purposes presently more fully appearing and as best seen in Figure 1. 35

Formed preferably integrally with and extending lengthwise across the upper portion of the machine bed or frame A midway between its lengthwise extending side walls or members a, is a cross bar a', thus dividing the upper portion of the frame into two similarly shaped rectangular openings B, the forward cross walls b of which are centrally cut away to provide clearance recesses 11, all as best seen in Figure 4 and for purposes presently more fully appearing. 45

The side members a, a', are machined along their inwardly presented faces to provide lengthwise extending horizontal guide channels or ways 50 55

12 having L-shaped cross-section and are each further provided at their inwardly presented vertical faces with a pair of preferably integrally formed laterally spaced vertical guide posts 13, 5 a small cam member *m* being rigidly mounted flatwise on the horizontal face of each of the ways 12 intermediate its ends, also for purposes presently more fully appearing and as best seen in Figure 4.

10 Mounted by screws or other suitable securing means flatwise on, and extending horizontally across the upper face of the machine bed or frame A, is a top plate 14 having a pair of parallel lengthwise extending rectangular apertures 15 C similar in width but somewhat shorter than, and for superposed registration with, the frame openings B and accordingly having a pair of outer side rails *c* and a central rail *c'* corresponding to the frame or bed members *a*, *a'*, 20 and co-operating therewith to form a top closure or retaining wall across the ways 12, all for purposes presently more fully appearing and as best seen in Figure 5.

25 Shiftably mounted in opposed relation at opposite ends of, and extending transversely between the ways 12 of each of the frame openings B, is a pair of rectangular plates or slides 15, 15', each machined out centrally of their adjacent transverse margins in the formation of relatively large 30 U-shaped openings 16, 16', the slides 15, 15', further being cut away on their under faces to provide flatwise extending recesses *r*, *r'*, for operatively accommodating pairs of companion shaping plates *s*, *s'*, which are retained in the slides 35 15, 15', respectively, for horizontally swingable movement by means of the pairs of pivot-ended retention screws 17, 17', threadedly mounted in the slides 15, 15', as best seen in Figures 2 and 3.

40 The pairs of shaping plates *s*, *s'*, each preferably comprise two similarly shaped flat rectangular steel plates cut away at respectively opposite corners in quarter-curve fashion, so that, when placed in edgewise abutment, the cut-out portions will match to form somewhat U-shaped 45 openings *o*, *o'*, conforming in contour to the desired shape of the shoe at the juncture line between the stitch-down flange and upper thereof, respectively, in the region of the heel and toe. Thus the pair of plates *s*, conforming 50 to the heel portion, may be referred to as the heel-shaping plates and the pair of plates *s'* may similarly be referred to as the toe-shaping plates. The straight abutting margins *t* of the plates *s* and the similar margins *t'* of the plates *s'* are 55 angularly machined off with respect to each other, so that the U-shaped openings *o*, *o'*, may be pivotally moved in a horizontal plane toward and away from each other about the pivot screws 17, 17', respectively, and will be laterally enlarged 60 when the outer side margins of the plates are parallel and in engagement with the vertical sides of the ways 12, all as best seen in Figures 6 and 7 and for purposes presently more fully appearing. The margins of the U-shaped openings *o*, *o'*, in both the toe and heel-shaping plates *s*, *s'*, are beveled or chamfered backwardly and outwardly from bottom to top to conform complementarily in cross-sectional shape to the cross-sectional shape of the outer faces of the stitch-down flange and shoe upper adjacent the juncture line therebetween, for purposes presently more fully appearing and as best seen in Figures 8 and 9.

75 Each of the slides 15' is provided centrally of its transverse margin with a suitable recess 18

for rotatively receiving the inner end of an adjustment screw 19 threadedly mounted in and extending outwardly beyond the adjacent side wall of the frame or bed A and being provided on its outwardly extending end with a suitably 5 knurled knob or handle 20, whereby the toe slide 15' and its associated shaping plates *s'* may be shifted lengthwise along the ways 12 toward and away from the heel slide 15 to any desired position of adjustment and retained in such adjusted 10 position. The slide 15 is provided centrally of its transverse margin with three horizontally aligned inwardly extending recesses 21, 22, 23, and an outwardly extending U-shaped horizontal frame 24 sized to project freely into the clearance 15 recess 11 of the frame-wall *b*. Mounted for axially shiftable movement in, and extending outwardly from, the recesses 21, 23, is a pair of parallel pins 25 provided at their outwardly extended ends with a transverse cross plate 26 abuttingly 20 engaging intermediate its ends a compression spring 27 mounted axially in, and extending outwardly from, the recess 22, whereby the plate 26 is normally urged outwardly toward the bight of the U-shaped frame 24, all as best seen in Fig. 25 3 and 4.

Rotatably mounted at their ends in the side walls *a* of the frame A and extending horizontally therebetween, is a pair of parallel horizontally spaced shafts 28, each being rigidly provided intermediate its ends with a pair of laterally spaced actuating levers 29 each positioned approximately midway of the respective frame openings B, the levers 29 of each of the shafts 28 being accordingly transversely aligned in pairs 35 longitudinally of the frame openings B and being further provided at their upper ends with a cam-like surface 30 and at their lower ends being bifurcated in the provision of a U-shaped slot 31, all for purposes presently more fully appearing 40 and as best seen in Figure 5.

Also rotatably mounted at its ends in, and extending horizontally between, the side walls *a* of the frame A preferably adjacent the forward legs 3, 4, is a shaft 32 rigidly provided intermediate 45 its ends with a pair of laterally spaced bell cranks 33, each having an upwardly extending or vertical leg 34 intermediately provided with a recess 35 and at its upper end provided with a tapered projecting arm 36 for engagement between the cross 50 plate 26 and the bight of the U-shaped member 24 of the bracket 15, the bell crank 33 further being provided with a horizontally extending arm 37 pivotally connected in the bifurcated end 33 of a diagonally extending link 39, which, is, in 55 turn, at its lower end pivotally connected to a horizontally extending foot lever 40.

The foot lever 40 is at its one end swingably mounted between the rear legs 1, 2, of the frame A by means of the shaft 41 and at its forward 60 end extends freely through and outwardly from the slot 9 and at its extended end is preferably integrally provided with a suitable pedal 42, the foot lever 40 further being apertured intermediate its ends for receiving one end of a tension 65 spring 43, which is, in turn, at its lower end attached to the cross-brace 5 of the machine frame or bed A for normally urging the foot lever 40 and its associated parts in upwardly disposed position. It may be further stated in this connection 70 that the foot lever 40 is of such width and longitudinal flexibility that it may be shifted laterally into the detent slot 10 for retention in downwardly depressed position against the action of the spring 43 when so desired by the operator, 75

all for purposes presently more fully appearing and as best seen in Figure 1.

Pivots mounted at one end in the aperture 35 of the crank arm 33 and extending outwardly therefrom, is a connection sleeve 44 sized for adjustably receiving one end of a horizontal link rod 45, which, at its other end, is pivotally connected to the proximate actuating lever 29. Pivots mounted at its opposite ends in the recess 10 31 of the companion actuating levers 29, is a horizontal link 46 adapted to connect the respective actuating levers for simultaneous movement, all for purposes presently more fully appearing and as best seen in Figure 3.

15 Loosely mounted on, and extending horizontally across, the cam surfaces 30 of each transversely aligned pair of the actuating levers 29, is a rectangular bed plate 47 cut away at its corners to fit snugly against and between the machine-frame guide posts 13 and being sized for somewhat loose fitting disposition within the machine-frame opening B for vertically shiftable movement therein. Mounted loosely on the upper face of the bed plate 47, is a similarly shaped and sized pressure plate 48 provided along its upwardly presented flat face with a depression or recess 49 shaped to conform to the desired contour of the sole-bottom of the finished shoe. It will, of course, be understood by those familiar 20 with the art that this sole-forming depression 49 may be omitted in the event that an entirely flat-bottomed shoe is desired.

In actual practice, it has been found that the so-called pressure plate and shaping plates should 35 preferably be varied in accordance with the size of the shoe which is to be manufactured, although it is not necessary that they should be varied or changed for each change in size.

By reason of the fact that the toe slides 15' 40 are shiftable to various positions of fixed adjustment, it is possible to utilize one set of shaping plates for a range of different sizes. By correspondingly shaping the sole-forming depression of the pressure plate to accommodate the largest 45 desired size, it is possible to use a single pressure plate and a single set of shaping plates as a unit for the accommodation of a given range of sizes. In fact, it has been found that three different sets of shaping and pressure plates are 50 sufficient to cover the entire normal range of children's stitch-down sizes with great accuracy.

It will, of course, be understood by those familiar with the shoe industry that the variety of 55 differently sized shaping and pressure plates will, to some extent, be governed by the volume of production in a given size and the quality of shoe being manufactured. If, for instance, a very high grade, expensive shoe is being manufactured, it may be desirable and profitable to 60 employ a different set of shaping and pressure plates for each different size of shoe. This may also be satisfactory and profitable in the manufacture of a very low priced shoe where relatively large quantities of a given size are produced at one time, so that it is not necessary to 65 change the plates too often.

In this connection, it should further be noted that the toe and heel slides 15, 15', of the one frame opening B may be fitted with shaping plates adapted for accommodation of right shoes, whereas the toe and heel slides 15, 15', of the other frame opening B may be fitted with shaping plates adapted for the accommodation of left shoes, so that at each operation a complete 70 pair of shoes may be processed.

The removal and change of the shaping and pressure plates are exceedingly simple and may be accomplished in a minimum of time. The toe slides 15' are pulled backwardly in the ways 12 by appropriate manipulation of the screw 5 19. The pivot screws 17, 17', are thereupon removed and the pairs of shaping plates s, s', respectively slid forwardly along the ways 12 out of the retaining recesses r, r', of the slides 15, 15'. With the shaping plates removed, it is 10 possible to reach down into the openings B and lift out the pressure plates 48 which are resting loosely on top of the bed plates 47. A different pressure plate is simply laid in place on top of the bed plate 47 and the correspondingly sized 15 sets of toe and heel shaping plates are slid along the ways into the retaining recesses r, r', of the slides 15, 15', and pivotally secured in place by the replacement of the pivot screws 17, 17'.

After the machine has been set up with the 20 appropriately sized shaping and pressure plates for the accommodation of the particular run of shoes to be manufactured, the slides 15' are shifted along the ways to a desired position of adjustment relative to the slides 15 for the accommodation of a particular size within the size-range. The outwardly turned or stitch-down flanges of the lasted shoe-uppers are coated with a film of suitable adhesive cement and the sole is thereupon applied thereto in simple abutting 30 fashion, forming an incomplete shoe D in which the upper is separated from the sole at its margin by a peripheral fissure d. In this condition, the shoes are conveyed or otherwise brought to the operator for further processing in accordance 35 with my present invention.

Each pair of such incomplete shoes D is placed, one in the one opening B and the other in the other opening B upon the upper face of the pressure plates 48 in more or less registration 40 with the depressions 49 thereof. The operator thereupon in quick succession depresses both of the foot levers 40 by stepping on the pedals 42 and, by sidewise shiftable movement of his foot, locking them in the detent slots 10. The downward movement of the foot lever 40 swings the diagonal link 39 downwardly, which, in turn, swings the horizontal arm 37 of the bell crank 33 outwardly, rotating the bell crank upon the shaft 32 and simultaneously shifting the sleeve 44 and the associated link 45 forwardly and urging the shiftable slide 15 forwardly in the ways 12. The horizontal shifting movement of the actuating link 45 accordingly rotates or swings the actuating levers 29 upon the shafts 28, moving the cam 55 surfaces forwardly along the under face of the bed plate 47. Since the bed plate 47 and its associated pressure plate 48 are both restrained against horizontal movement by the guide post 13, they are accordingly elevated upwardly while 60 being maintained constantly in a horizontal position as the slide 15 and its associated shaping plate is moved forwardly.

As the slide 15 and the associated pair of shaping plates s approach their forwardmost limit of 65 travel, the outer longitudinal margins of the shaping plates s ride over the fixed cam members m and are accordingly swung inwardly about the pivot screws 17 for squeezing action around the heel portion of the shoe. This latter movement is necessarily arranged to occur at that moment of time when the mid-point s'' has just engaged the rearmost portion of the heel of the shoe upper. At this point of time, the shoe will be held tightly 70 between the toe and heel shaping plates at its 75

toe-tip and heel-tip. The further forward movement of the slide 15 will cause the toe-tip of the shoe to press forwardly at the mid-point s'' of the toe-shaping plates s' , thereby automatically pivoting them about the retaining screws 17 for squeezing action around the toe portion of the shoe.

Meanwhile, the pressure plate 48 will have been elevated almost to its uppermost level of movement. At its uppermost level of movement, the pressure plate 48 must be so spaced vertically downwardly from the under face of the shaping plates that the out-turned or stitch-down flange of the shoe upper will be tightly squeezed against the upper face of the shoe sole, as best seen in Figure 9. During the few instants of time in which the rising pressure plate 48 is approaching its upper limit of travel, the shaping plates are squeezing inwardly upon the toe and heel portions of the upper. Since the pressure plate and the shaping plates are moving relatively toward each other, the resultant effect of this movement upon the shoe upper is actually to pull the upper downwardly more tightly over the last as the flange thereof is being squeezed against the shoe sole. The heel pressure plates s , having reached their forward limit of travel, will normally come to rest and the vertical arm 36 of the bell crank 33 will continue its forward motion against the bias of the spring pressed plate 26, whereby to permit a further final upward movement of the pressure plate to insure compressive deformation of the shoe sole between the downwardly presented face of the shoe last and the depression 49 in the upwardly presented face of the pressure plate 48.

As this series of operations is completed, the foot lever 40 is locked in downwardly disposed position in the detent slot 10 and the shoe is held in vise-like grip of the machine for any desired interval of time to allow the cement to harden or set. While this is taking place, the other shoe of the pair is being similarly shaped and formed by the depression of the companion foot lever 40, which sets in motion a similar and identical series of movements in the manner above described.

By the use of any one of a number of highly satisfactory quick-setting cements available to the shoe industry, it becomes unnecessary to retain the shoes in gripped position within the machine for a very long space of time. In fact, it has been found that the first shoe operated upon will be thoroughly set and may be released from the machine by the time the second shoe of the pair has been shaped and completed by the compression of the second foot lever 40 and it has been further found that, while the first shoe is being released and removed from the machine, the setting of the cement in the second shoe will be completed, so that, by the time the first shoe is removed, the removal of the second shoe may also be started.

The removal of the shoes is accomplished by simply shifting the foot lever 40 out of the detent slot 10 and allowing it to be pulled upwardly to initial position under the influence of the spring 43. As the lever moves upwardly, the horizontal arm 37 of the bell crank 33 will be swung upwardly, reversely rotating the bell crank and shifting the vertical arm 34 backwardly, withdrawing the slide 15 and its associated shaping plates, s, s' , and simultaneously lowering the pressure plates to initial position, whereupon the shoe may be lifted out of the machine and is ready for final stitch-

down operations by which the upper and sole are secured together by either a single or double line of stitches and either with or without the welt strip w , as may be desired and as best seen in Figure 10.

In the preferred embodiment above discussed, I have found it desirable to form the slides 15, 15', and the associated pairs of toe and heel-shaping plates s, s' , of such length that they will not entirely embrace the shoe when in operative engagement therewith but will be separated at their opposed transverse margins by a substantial distance on either side of the shoe in the region of the instep or arch thereof, as best seen in Figure 9. It is, of course, possible to provide slides and shaping plates of such size and form that they will actually meet and entirely embrace the shoe. This, however, would make necessary a change of shaping plates for each change in size or shape of the shoe itself and would materially limit the flexibility of the machine. As was above pointed out, three different sets of shaping plates may be satisfactorily utilized to cover a broad range of sizes by reason of the fact that the slides 15' and the toe-shaping plates associated therewith may be shifted forwardly and rearwardly in the slides to varying positions of adjustment with respect to the slides 15 and the heel-shaping plates s by means of manipulation of the adjustment screws 19. Under these latter conditions, I have found that it is desirable to finish off the shoe once it has been gripped in the machine by manually pressing the unembraced instep portions of the stitch-down flange by use of a roweling tool or other suitable instrument. It is also possible to accomplish this result by suitable machinery, which forms the subject-matter of a separate application for Letters Patent of the United States presently to be filed by me.

In some cases, it may be desirable to reverse the toe plates and heel plates, so that the toe plates s' are mounted in the slide 15 and the heel plates s are mounted in the slide 15', in which case the toe plates will be moved into the toe of the shoe for lasting operation. This has been found desirable in the case of lasts of certain types and shapes, but is clearly within the scope of the present invention, being a mere reversal of parts.

By my present invention, I have thus provided a means and method for attaching uppers and soles of shoes of the type stated, which is exceedingly simple, efficient, and speedy and which actually brings the shoe upper and sole into much more close fitting abutment. In fact, by my present invention, it is actually possible to complete the lasting of the shoe by pulling the shoe upper more tightly over the last as it is brought into sole engagement. It is furthermore possible by my present invention to provide a sharper, more acute-angled marginal recess between the upwardly curving outer face of the upper and the flat upwardly presented face of the out-turned or stitch-down flange, as at v in Figure 10, so that the welt strip w may actually be forced tightly thereinto in the formation of a very close fitting structure having exceptionally desirable wearing qualities.

It should be understood that changes and modifications in the form, construction, arrangement, method, and combination of the several parts of the shoe-forming machine may be made and substituted for those herein shown and de-

scribed without departing from the nature and principle of my invention.

Having thus described my invention, what I claim and desire to secure by Letters Patent is,

5 1. A shoe-forming machine comprising a base, vertically shiftable means on the base for supporting the sole of a shoe, a pair of companion-shaped slides mounted on the base for horizontally shiftable movement, and co-operative means 10 freely pivoted on each of the slides for shiftable movement therewith for compressively superposing the lower margins of the shoe upper upon the sole.

15 2. A shoe-forming machine comprising a base, vertically shiftable means on the base for supporting the sole of a shoe, a pair of companion-shaped slides mounted on the base for horizontally shiftable movement, and co-operative means 20 freely pivoted on each of the slides for shiftable movement therewith and being relatively swingable toward and away from each other for compressively superposing the lower margins of the shoe upper upon the sole.

25 3. A shoe-forming machine comprising a base, vertically shiftable means on the base for supporting the sole of a shoe, a pair of companion-shaped slides mounted on the base for horizontally shiftable movement, co-operative means 30 freely pivoted on each of the slides for shiftable movement therewith and being relatively swingable toward and away from each other for compressively superposing the lower margins of the shoe upper upon the sole, and driving means for simultaneously moving the slides relatively toward each other and toward the sole-supporting means.

35 4. A shoe-forming machine comprising a base, vertically shiftable means on the base for supporting the sole of a shoe, a pair of companion-shaped slides mounted on the base for horizontally shiftable movement, co-operative means 40 freely pivoted on each of the slides for shiftable movement therewith and being relatively swingable toward and away from each other for compressively superposing the lower margins of the shoe upper upon the sole, and driving means for simultaneously moving the slides and the sole-supporting means relatively toward each other.

45 5. A shoe-forming machine comprising a base, vertically shiftable means on the base for supporting the sole of a shoe, a pair of companion-shaped slides mounted on the base for horizontally shiftable movement, co-operative means 50 freely pivoted on each of the slides for shiftable movement therewith and being relatively swingable toward and away from each other for compressively superposing the lower margins of the shoe upper upon the sole, and driving means for simultaneously moving the slides relatively toward each other and the sole-supporting means 55 relatively toward the slides.

60 6. A shoe-forming machine for attaching uppers to soles comprising a base having a pair of parallel ways, a pair of slides mounted for shiftable movement toward and away from each other in the ways, each of said slides being provided with a pair of pivotally mounted flatwise disposed plates cut away in the provision of an aperture contoured for snug embracing conformation to a selected segment of the desired curve of a finished shoe upper along the juncture line between the upper and the sole, and a plate mounted in spaced juxtaposition with the slides for bodily shiftable movement toward and away 65 from the slides, said plate having in its upper face

a depression contoured for conformation to the desired shape of the sole-bottom in the finished shoe.

7. A shoe-forming machine for attaching uppers to soles comprising a base having a pair of opposed parallel, horizontal ways, a pair of slides mounted for shiftable movement toward and away from each other in the ways, a plate mounted in subadjacently spaced juxtaposition with the slides for bodily shiftable movement toward and away from the slides, and means for simultaneously moving the slides relatively toward each other and shifting the plate bodily toward the slides initially at a relatively rapid rate of speed and finally at a relatively slow rate of speed.

10 8. In a device of the character described, in sub-combination, a shiftable slide having a pair of companion-shaped flat shoe-shaping plates contoured for embracing engagement with a selected portion of a shoe, said plates being pivotally mounted in the slides for free-swinging movement about fixed points spaced substantially from, and respectively on opposite sides of, the longitudinal center line of said slide and being adapted for initial engagement with the shoe at 15 a selected point as the plates and the shoe relatively approach each other during shaping operation whereby to cause automatic inwardly swinging movement of the plates upon further relative approach of the shoe for exerting squeezing pressure on the shoe.

20 9. A shoe-forming machine comprising a base, a first slide-member shiftably mounted on the base, a second slide-member shiftably mounted on the base for movement toward and away from the first slide-member, each of said slide-members being provided with wiper plates respectively contoured for embracing engagement with opposed portions of a shoe-upper in the region of the sole-engaging margin thereof, a sole-engaging plate shiftably mounted in the base for bodily movement toward and away from said slide-members, means co-operable with the first slide-member for adjustably setting said slide-member at any selected position with respect to the base, 25 and means for simultaneously shifting the second slide-member and the sole-engaging plate toward the first slide-member.

30 10. A shoe-forming machine comprising a base, a first slide-member shiftably mounted on the base, a second slide-member shiftably mounted on the base for movement toward and away from the first slide-member, each of said slide-members being provided with wiper plates respectively contoured for embracing engagement with opposed portions of a shoe-upper in the region of the sole-engaging margin thereof, a sole-engaging plate shiftably mounted in the base for bodily movement toward and away from said slide-members, means co-operable with the first slide-member for adjustably setting said slide-member at any selected position with respect to the base, 35 and means for simultaneously shifting the second slide-member and the sole-engaging plate toward the first slide-member.

40 11. A shoe-forming machine comprising a base having a pair of opposed parallel slide-ways, 45 a first slide-member shiftably mounted in the ways, a setting-member operably connected to the first slide-member and threadedly mounted in the base for shifting the first slide-member to any selected position of adjustment along the 50

ways and holding said slide-member at such selected position, a second slide-member shiftably mounted in the ways for movement toward and away from the first slide-member, a bell-crank swingably mounted in the base and being connected at one end to said second slide-member, means operably connected to the bell-crank for producing rocking movement thereof whereby to shift the second slide-member along the ways, wiper means removably mounted in each of the slide-members, said wiper means being complementarily contoured respectively for embracingly engaging the opposed portions of a

shoe-upper in the region of the sole-engaging margin thereof, a sole-engaging plate mounted for shiftable movement toward and away from the plane of the slide-ways, a pair of rotatable cam-members operatively engageable with the plate for bodily shifting the plate toward and away from the plane of the slide-ways, a link operably connecting said cams for simultaneous movement, and means connecting said cams to the bell-crank for producing sole-plate shifting movement thereof simultaneously with slide-shifting movement of the bell-crank. 5 10

OTTO ANTHONY DEHNE.
